RUBBER FEEDING MEANS FOR CIRCULAR
KNITTING MACHINES

Albert E. Page and Frank R. Page, Brooklyn,
N. Y., and Harry N. Sheppard, Maplewood,
N. J., assignors to Scott & Williams, Incorporated,
New York, N. Y., a corporation of Massachusetts

Application March 27, 1935, Serial No. 13,328

27 Claims. (Cl. 66—12)

This invention relates to circular knitting machinery and more particularly to mechanism for laying rubber yarn in the fabric during the making of the fabric and it is an object of this invention to provide a machine of the type described having improved mechanism for laying rubber yarn in the fabric and for controlling the operation thereof. It is also an object of the invention to provide means whereby the usual knitting instrumentalities are operated to insure the insertion of the rubber yarn in the fabric at the proper point and hold the rubber yarn in proper feeding relation with the needles knitting the fabric and it is also an object of this invention to provide means whereby the means controlling the rubber yarn can be used for other purposes when the rubber yarn is not being fed without causing the operation of the rubber yarn feeding means. It is a further object of the invention to provide means for introducing the rubber yarn to the machine substantially without tension to aid in introducing the rubber yarn at the proper point in the fabric and to render the use of yarn-measuring devices on the rubber yarn feed unnecessary. The invention is shown and described as embodied in the well-known Scott & Williams revolving needle cylinder half hose knitting machine, such for instance as shown in the patent to Robert W. Scott No. 1,641,101, dated August 30, 1927, but it should be understood that the invention is not limited to revolving needle cylinder machines or to machines for making half hose.

In the drawings,

Fig. 1 is an elevation of the left side of sufficient of a Scott & Williams half hose knitting machine to show the rubber yarn finger and special needle controlling cams and their controls, some of the standard parts being shown in dotted lines;

Fig. 2 is a partial view, partly in side elevation from the right side of the machine and partly in section, showing the dial and some of the controlling mechanism associated therewith;

Fig. 3 is a plan of a portion of the dial with the dial cap removed showing the relation of the rubber yarn and the dial needles;

Fig. 4 is a development of the edge of the dial shown in Fig. 3 after the feeding of the yarn has progressed a little further than is shown in Fig. 3; the dotted line position of the rubber yarn being that assumed by the yarn when the finger feeding the rubber yarn has just been raised to idle position and the rubber yarn has gotten into the cutter but has not yet been clamped or cut;

Fig. 5 is a development similar to Fig. 4 showing the position of the rubber yarn with respect to a

special starting needle for the rubber yarn just prior to the time that the special starting needle takes the yarn.

Fig. 6 is a plan view of the dial showing the yarn finger and associated controls;

Fig. 7 is a partial sectional view taken just above the lower bedplate and showing the cams and controls which operate the special starting needle;

Fig. 8 is a side elevation of the yarn finger and slack-producing guide, showing each element in its lowermost position;

Fig. 9 is a vertical section through one edge of the dial showing the relative positions of the dial, sinker, needles and rubber yarn;

Fig. 10 is a development of so much of the auxiliary pattern drum cam layout as is necessary for an understanding of this invention;

Fig. 11 is a similar development of part of the main pattern drum layout; while

Fig. 12 is a view in side elevation of the mechanism by which the rotation of the auxiliary drum is controlled from the main drum.

When it has been desired to put rubber yarn in any knitted fabric, great difficulty has been encountered in feeding the yarn properly because the elasticity of the yarn rendered the ordinary tensioning devices unsuitable for controlling the feeding of the yarn. Rubber yarn has usually been fed in a knitting machine, therefore, by a measuring device, such as rolls whose speed is adjusted to produce the proper tension on the rubber yarn. These devices involve a considerable number of parts and their control and are unsatisfactory in many ways. This invention provides a simple means for feeding rubber yarn by which the yarn can be controlled so as not to produce faulty fabric, and to achieve this end the mechanism guides and controls the rubber yarn so as to introduce the yarn to the fabric without tension.

The invention is shown embodied in a machine of the aforementioned Scott Patent No. 1,641,101 which is provided with the selecting mechanism shown in the patent to Ivan W. Grotthey, No. 1,678,385. The machine disclosed embodies the usual needle cylinder 260, upper and lower bedplates B and B', respectively, a main pattern drum 120, auxiliary pattern drum 20, cylinder needles N and N' mounted in the needle cylinder 260 and dial needles a, b, mounted in the dial D. There are also the usual latch ring 550 and outside sinker ring 300.

In a machine constructed in accordance with this invention the rubber yarn is introduced into the fabric without being placed under appreciable

tension and it is one of the features of this invention that means are provided to avoid the difficulties which ordinarily arise when rubber yarn is introduced into the fabric under tension. The 5 invention contemplates that the rubber yarn will not be knit into the fabric but will be laid in the stitches and in the example of the invention shown in the drawings and described hereinafter the rubber yarn 18 is shown laid in the ribbed 10 top of a half hose just below the welt. In order that the yarn may be laid in this position in the fabric the yarn is fed from a special yarn finger 185, shown in Figures 4 and 5, which delivers the yarn just below the hook portion *a* of the 15 dial needles *a*, *b*, as shown for instance in Figure 9. In this location the rubber yarn 18 lies between the dial needles *a*, *b* and the cylinder needles *N*, *N*¹ and is incorporated in the fabric by being caught between the loops of the rib and 20 plain wales. The fabric as it is knit is fed down between the dial *D* and needle cylinder 260 by the action of the teeth *w*¹³ on the sinkers *w* as shown in Fig. 9 and special means are provided to separate the dial and needle cylinder so that 25 the fabric containing the rubber yarn can be readily led away in this manner.

In order to insure that the rubber yarn shall be introduced at the proper point in the fabric means are provided to grip the yarn and hold it in 30 proper position either long enough to insure the operation is properly started or throughout the feeding of the rubber yarn to the fabric. It has heretofore been known to employ one or more of the needles used in knitting the fabric to grasp 35 the rubber yarn and hold it, but this is objectionable in that such needles must, of necessity, pass through the feeding wave shortly after they take the rubber yarn and the release when the needles clear is too soon after the taking of the rubber 40 yarn to insure that the yarn stays in its proper position. In accordance with this invention there is employed to hold the rubber yarn a needle which, during rib knitting, is normally in idle position, namely one of the cylinder needles which 45 is out of action during the making of rib fabric in order that the dial needles *a*, *b* may operate. It will be noted, for instance, in Figure 5 that the special needle *N*² is opposite one of the dial needles *a*, *b* and therefore normally would be idle 50 during the making of rib fabric. We have discovered, however, that by proper manipulation this idle cylinder needle can be employed to hold the rubber yarn and yet avoid interference with both parts of the dial needles during the knitting 55 of rib fabric.

This is accomplished by causing the special idle cylinder needle or needles *N*² to be raised at a point slightly in advance of the position of the finger 185 feeding the rubber yarn. The special needle *N*² is raised to such a height that shortly after it passes the special rubber yarn feeding finger 185 which lies just outside the needle circle, as shown in Fig. 3, it will contact with that portion of the rubber yarn 18 lying between the finger 185 and the cutter and clamp mechanism *C* which is located inside the needle circle, as shown in Fig. 6. Immediately after taking the yarn the needle *N*² is pulled down so as to draw the yarn below the dial needles. Since this needle is 60 not used to knock over stitches at this time, the yarn can be held in the needle hook until the length of fabric knit draws the free end of the yarn from the hook. If it is desired that the idle cylinder needle which takes the rubber yarn when it is first fed to the machine continue to hold

the free end of the rubber yarn throughout the feeding operation, this needle can be prevented from rising at the usual transfer and tuck points during the courses the rubber yarn is fed. In order to prevent this needle from rising at these 5 points, the usual transfer and tuck cams (not shown) can be made movable to be withdrawn during the making of the rib fabric and any usual mechanism can be employed for this purpose.

Needle raising cam and mechanism controlling it 10

The mechanism for manipulating the needle or needles to take the rubber yarn when it is introduced will now be described. As shown in Fig. 7, there is provided an auxiliary draw down 15 cam 8 supported by a pivotally mounted bracket 183 at a point slightly in advance of the feeding position of the rubber yarn which cam, when inserted, will draw down all the cylinder needles. Also mounted on the bracket 183 is a special isolating or raising cam 184 which, when the draw down cam 8 is inserted all the way, will engage long butt cylinder needles but will miss medium and short butt cylinder needles. The cylinder needles are arranged in such manner 20 that the only long butt cylinder needles are the needle or needles *N*² which are to take the rubber yarn 18 and it therefore follows that the isolating or raising cam 184 will raise only the needle or needles which are to take the rubber yarn when 30 it is introduced in the fabric. The isolating cam 184 raises the needles *N*² slightly in advance of the position of the rubber yarn feeding finger 185 as already described and the needle or needles *N*² are lowered again by stationary cam 151 35 located at a point diametrically opposite the knitting point.

The isolating or raising cam 184 has both a primary and a secondary control means. The primary control means, which is operated from 40 cams on the main pattern drum 120, has several functions, but as far as these functions concern the isolating cam 184, the primary control means merely serves to move the cam 184 from fully retracted position to an intermediate position 45 where it just misses the long butt needle *N*². The actual movement of the isolating cam 184 from this last-mentioned or intermediate position to operative position is accomplished by the secondary control means. The primary control means 50 are actuated by cams on the main pattern drum comprising high cams 523, 525 and 526 and low cams 524 and 527, Fig. 11. These cams actuate a lever 461 pivoted just above the main drum 120. The upper end of the lever 461 has fastened 55 thereto one end of a wire 177 which overlies the upper bedplate *B* (Figs. 1 and 7) and has its other end connected to one end of the pivoted support of an auxiliary clearing cam 26. The wire 177 is connected to the isolating cam 60 184 through an upright lug or stop 176 on the wire 177 which lies in the path of a pin 178 extending laterally from the bracket 183 which carries the isolating cam 184 and the auxiliary draw down cam 8. The bracket 183 is pressed 65 toward operative position for the two cams 8 and 184 by a coil spring 182. The lug or stop 176 when operated to shift the pin 178 to the left in Fig. 7 draws both cams 184 and 8 out of operative relation with the cylinder needle butts. 70 Owing to the presence of the secondary control mechanism which will next be described, the operation of the lever 461 when it rides up on to or down off a low cam does not affect the positions of the cams 8 and 184, the low cams being 75

used in connection with the operation of the auxiliary clearing cam 26.

The secondary control means which determines accurately the operative positions of cams 8 and 184 include a blade 180 carried by a lever 179 so as to be eccentrically mounted with respect to the pivot point 181. The lever 179 is connected by a link to a rod 460, the lower end of which is so attached to a bell crank lever 14 operated by cams on the auxiliary striping drum 20 that the rod 460 operates as an arm of the lever 14. This secondary control means has two positions the first of which is shown in Fig. 7 and in this position the blade 180 holds the pin 178 so as to determine the innermost operative position of the cams 8 and 184. In this position the draw down cam 8 has a long overlap with the needle butts and is in a position to draw down all the cylinder needles while the isolating cam 184 is in position to elevate the long butt needles N². This position of the cams is assumed only when the bell crank lever 14 associated with the rod 460 is on a cam 859 (see Fig. 10). The cam 859 is so located with respect to the racking means for the auxiliary drum 20 that the isolating cam 184 is inserted to the position shown in Fig. 7 and retracted again during one rack of the auxiliary drum 20. As soon as the bell crank lever 14 associated with the rod 460 rides off the cam 859 onto the surface of the drum 20, the blade 180, turning about its pivot point 181, pushes the pin 178 sufficiently to move the isolating cam 184 out of the path of the long butt needle N² but not enough to move the draw down cam 8 out of operative relation with the short and medium butt needles. There being no cams other than cam 859 on this cam path on the drum 20, the blade 180 acting through the pin 178 serves to insure that the isolating cam 184 does not raise the needle N² again. In this way the needle or needles N² are raised to take the rubber yarn on only one revolution.

The racking of the auxiliary striping drum 20 is so timed that the auxiliary draw down cam 8 and the isolating cam 184 are moved into their operative positions about one-third of a revolution before the long butt cylinder needle N² reaches the isolating cam 184 and about two-thirds of a revolution of the needle cylinder later the isolating cam 184 is moved back out of operative position. The racking of the auxiliary pattern drum 20 is accomplished by the usual rack wheel 21 at an end of the drum 20 and the pawl and heart-shaped cam shown in dotted lines near the bottom of Fig. 1. The idling mechanism for this racking means is shown in Fig. 12.

In the arrangement of parts just described, the long butt needle N², after once taking the rubber yarn, holds the yarn in its hook until the length of the rib fabric knit pulls the free end of the yarn from the needle.

Rubber yarn feed

The finger 185 for feeding the rubber yarn 18 and the means for manipulating that finger will now be described. In order that the finger 185 may be lowered to feeding position shortly after the welt has been knit and then raised out of action after the desired number, as 8 or 10 courses, have been knit to stay out for the balance of the knitting of the hose, the finger 185 is pivotally mounted and raised and lowered by cams on the auxiliary striping drum 20. The finger 185, as shown, is tubular and if desired can be cut away through part of its length, as

in Fig. 1, to make it easier to thread the rubber yarn. The finger 185 is located at the same point that is customarily used in feeding a yarn for making the fashion seam, as shown in the patent to Scott, No. 1,256,834, issued February 19, 1918. The finger 185 is mounted on a lever 142 which is pivoted on the latch ring 550 and is provided with an adjustable stop 143 engaging the top of the latch ring. The yarn finger 185 is biased to a raised position by a tension spring 144 extending between the lever 142 carrying the finger and any suitable fixed part of the machine, or as shown in Fig. 8 to an arm 145 mounted on the cover of the horizontal gear for the rib dial (not shown). The yarn 18 passes through a 15 hole in this arm 145. The connection between the lever 142 pivoted on the latch ring 550 and the auxiliary drum 20 consists of a bent thrust rod 462 attached to a rigid arm 142^a on the lever 142 and to a bell crank 14 associated with 20 one of the cam paths on the auxiliary striping drum 20. These parts are so adjusted that when the toe of the bell crank lever rides on to a cam the yarn finger 185 is lowered into operative position. The finger 185 is timed to be lowered 25 on the same rack of the auxiliary striping drum 20 as brings the isolating cam 184 into operative position. This rack of the auxiliary striping drum is started at the end of the welt as a result of a rack of the main pattern drum 120. 30

Safety device for rubber yarn finger

It is necessary to be sure that the rubber yarn feeding finger 185 is not moved into operative position except during the knitting of rib fabric. 35 If it should come down at the wrong time, owing to an improper rack of the auxiliary striping drum, the main drum, or pattern chain finger, damage to some of the parts of the machine might result. A safety device has therefore 40 been provided in connection with the bell crank lever 14 and the bent thrust rod 462 which operates the yarn finger 185. Between the bell crank lever 14 and the bent thrust rod 462 there is a pin and slot connection 45 146, the slot being vertical in the thrust rod and the pin being carried by the crank lever 14 and engaging in the slot, and the connection is such that tipping the bell crank lever 14 will not raise the bent thrust rod 462 except when 50 means are made effective to prevent movement of the pin in the slot. The means provided consist of a latch 147 pivoted on the bent thrust rod at a point above the slot and having a catch or shoulder 148 facing toward the stub end of the 55 bell crank lever. The latch 147 is biased by a short spring 149 attached to the lower end of the bent thrust rod 462 to a position above the bell crank lever arm in which it holds the pin on the bell crank lever at the bottom of the slot so that 60 any movement of the bell crank lever will cause the latch to raise the bent thrust rod.

It is necessary that this latch be released at all times except during the knitting of rib fabric in order to protect the machine from damage by 65 the engagement of the rubber yarn finger with the needles and other parts and to this end the following connection is provided. The latch 147 has a curved laterally projecting arm 147^a extending toward the front of the machine close 70 beside another thrust rod 463, shown best in Fig. 1, which is operated only during knitting of rib fabric to increase the stroke of the toothed sinkers by means of the wire 135 and cams 375, 376 shown in Fig. 6. The thrust rod 463 at all times, 75

except during the knitting of rib fabric and at the transfer to plain fabric, rides on a high cam 521 (Fig. 11) on the main pattern drum 120. During the making of rib fabric it rests on the surface of the drum 120 as shown in Fig. 11, and during transfer from rib to plain fabric it rests on the low cam 522. Projecting from one side of the thrust rod 463, just below the arm 147 of the latch, is a pin 150 which is so positioned vertically that it is below and clear of arm 147^a when the thrust rod 463 is on the surface of the main pattern drum 120 but when the thrust rod 463 is on cam 522 or cam 521 the pin 150 engages the arm 147^a and tips the latch 147 until its shoulder 15 is out of engagement with the arm of the bell crank lever 14. This frees the bell crank lever to move the pin idly in the slot in the push rod, thus allowing the bell crank lever to be operated without causing any movement of the yarn finger lever 142 so that the latch 147 prevents the bent thrust rod 462 moving the rubber yarn finger into operative position except during the knitting of rib fabric. At all other times an improper rack of the striping drum 20 will not cause any movement 25 of the rubber yarn feeding finger.

Rubber yarn guiding means

Experience has shown that the length of rubber yarn 18 lying between the knitting point and the yarn finger 185 will, especially if not under tension, vibrate to an extent which causes the yarn to be caught on some knitting instrumentality. To avoid this, the dial needles are employed to hold the rubber yarn in position thus providing a guard means which is simple and easy to manipulate without increasing the number of elements in the machine at the point where the knitting operation takes place. This is accomplished by projecting the hook portions *a* of the dial needles *a*, *b* beyond the verge of the dial D a distance of one-sixteenth of an inch at a point shortly after the feeding position of the rubber yarn. It is impossible to keep these dial needle hooks out such a distance until they are projected 45 to take the yarn unless the transfer and tuck cams are withdrawn because at a point shortly after the hook portions are projected the inactive cylinder needles N¹ are usually raised prior to passing under the dividing cam, as by the transfer and tuck cams 25 and 40, respectively, of Patent No. 1,641,101, along with the active cylinder needles and the inactive needles are aligned with the dial needles and would contact therewith. However, if a few of the dial needles nearest the 55 yarn feeding finger are projected a sixteenth of an inch thereafter a projection of a lesser degree will suffice to hold the rubber yarn in position below the dial needles. In accordance with this invention, therefore, there is provided, as shown in Fig. 3, a pivoted cam 152 which pushes the dial needle hooks *a* out for one-sixteenth of an inch shortly after they pass the rubber yarn feeding finger 185 and keeps only 3 or 4 dial needle hooks so extended at the same time. A guard cam 153 is provided following the pivoted push-out cam 152 which retracts the dial needle hooks to a position where they extend only about one thirty-second of an inch beyond the verge. In this position they are sufficiently retracted to avoid contact with the inactive cylinder needles N¹ and yet they overlie the rubber yarn sufficiently to hold it in position. The long butt needle or needles N² are drawn down by the cam 151 before the dial needles are projected.

75 The mechanism for moving the pivoted cam

152 into and out of action, shown best in Figs. 1 and 6, is actuated from the lever 142 carrying the rubber yarn feeding finger 185. Fastened on top of the lever 142 is a laterally projecting blade 154 located about the middle of the lever which overlies the upper end of a short crank 155 pivoted on a bracket 156 carried by the latch ring 550 (Fig. 1). The lower end of the short crank 155 engages the side of the bent up end of a curved plate 157. The other end of this curved plate is pivoted on the dial cam cap (Fig. 6) and the mid-point thereof is fastened to a pin 158 in the free end of the pivoted cam 152 which acts on the hook portions *a* of the dial needles (Fig. 3). The lowering of the rubber yarn feeding finger to operative position causes the blade 154 to push down on the short crank 155 swinging the curved plate 157 outward and carrying the pivoted cam 152 of Fig. 3 outward so as to push the hook portions *a* of the dial needles outward until they extend one-sixteenth of an inch beyond the verge to hold the rubber yarn in its proper position.

Rubber yarn tension reducing means

As the needles N² rotate they tend to pull the 25 end of the rubber yarn from the clamp which has been holding it since the yarn was cut off in the previous hose and the needles also tend to stretch the yarn. As a result of being stretched when the yarn is pulled or released 30 from the clamp the free end of the yarn tends to snap back from between the needles and the sinkers and come out of the yarn guide. It is necessary, therefore, when introducing a plain rubber yarn with a high degree of elasticity to 35 insure that there is little or no tension on the yarn, particularly at the moment when feeding is begun, and to this end a novel guiding means is employed in association with the yarn finger, as can be seen from the diagrammatic showing 40 in Fig. 6.

The rubber yarn supply may be mounted at the rear of the machine and the rubber yarn fed over one or more guides which change its direction until the yarn is finally presented to the 45 yarn finger or the yarn supply may be mounted in position to feed directly to the yarn finger 185. Either arrangement gives a path of travel of a certain length for the rubber yarn. By dipping one of the guides, and preferably the one 50 just previous to the yarn finger, i. e., changing its position, or by shifting the yarn supply towards the yarn finger, the length of the path of travel of the rubber yarn can be shortened and if this operation is performed at just the 55 proper time, the rubber yarn is relieved of all, or most of its tension, and will feed into the mechanism heretofore described, without any trouble. By thus lowering the last guide toward the needles and returning it to its original 60 position in the specific timed relations which will now be described, all danger of the yarn pulling out or having an abnormal tension at the beginning of the feed is avoided.

Referring now more particularly to Fig. 8, 65 the yarn guide arm 190 shown has a tension disk device 191 for the rubber yarn which passes from the tension device through a small hole in the end of the arm 145. Before the rubber yarn finger 185 is lowered to operative position 70 from the dotted position shown in Fig. 8, the yarn guide 191 is in its uppermost position. It is preferred to lower the yarn guide 191 from its uppermost position to its intermediate position shortly after the isolated needles N² have 75

grasped the rubber yarn, and specifically about the time that the needles N^2 are passing the cutter and clamp mechanism C. If the movement of the yarn guide 191 at this time is made 5 large enough to provide all the slack needed, a loop of the rubber yarn is sometimes thrown over the dial needles instead of under them. It is advisable, therefore, to provide only some of the necessary slack at this time and to provide 10 a second step about the time that the clamp mechanism C opens. To mount the yarn supply for feeding directly to the yarn guide, a lightly frictioned reel or spool may be mounted on the arm 190 in place of the guide 191 so as 15 to feed the yarn directly to the yarn finger 185.

In practice, the guide 191 and arm 190 can be kept in their lowermost positions during the remainder of the feeding of the rubber yarn, but it is found preferable to raise the arm and guide 20 to their uppermost positions shortly before the feeding of the rubber yarn ceases. The raising of the guide at this time does not cause any increase in the tension of the yarn and gathers slack for the next stocking before the rubber 25 yarn is cut out in the stocking just being finished. It will be noted that the movement of the guide can be controlled to give the amount of slack desired and when desired.

For moving the guide 191, means controlled 30 from the auxiliary striping drum 20 are provided. The guide arm 190 is a long arm pivoted at a point 193 at the rear of the machine (Fig. 1) and having a tension spring 194 tending to hold the arm in its uppermost position. Attached to the arm 190 is a link 195 connected to a bell crank lever 14 actuated by cams on the auxiliary striping drum 20 in such manner that when the bell crank lever 14 drops from a high 35 cam to a low cam, the guide 191 is lowered half way and when the bell crank lever 14 drops onto the surface of the auxiliary pattern drum 20, the guide 191 is lowered to its lowermost position. In practice the lowering of the guide 191 from its upper to its intermediate position, occurs 40 practically simultaneously with the lowering of the yarn finger 185 to its operative position, and about one-third of a revolution later the guide is lowered to its lowermost position.

50 Cylinder and dial spacing mechanism

The portion of the fabric containing the rubber yarn is considerably thicker than the rest of the fabric of the half hose and the space 55 between the fins on the dial D and the teeth on the sinkers w is insufficient to allow the fabric to pass readily between the dial and needle cylinder down to the fabric tube. Allowance for the difference in thickness of the fabric due to adding the rubber yarn can be made by lowering the needle cylinder during 1 x 1 rib knitting without changing the length of stitch.

To thus make more room for the finished fabric and allow the rubber to be fed at the unusually 60 low point necessary, a cylinder raising lever 196 is pivotally mounted on the lower end of the cylinder raising tube 197. In one end of this lever is an adjusting screw 198 which rests on a stationary portion of the frame of the machine, 65 namely, the cylinder tube support bracket, so that movement of the lever 196 causes the cylinder raising tube to be raised or lowered. The other end of the lever 196 is fastened to a link 199 which in turn is connected to an arm of a bell 70 crank lever 14 associated with the auxiliary

striping drum 20. This linkage is so arranged that when the bell crank lever drops off its cam to its lowermost position against the surface of the auxiliary striping drum 20, the needle cylinder 260 is dropped to its lowermost position. This occurs as the machine starts to make the rib fabric and the striping drum 20 is causing the rubber yarn finger 185 to be lowered to operative position. After the desired number of courses of rib fabric with rubber laid in are made, a cam on the striping drum 20 operates the bell crank lever raising the lever 196 and causing the cylinder raising tube 197 to be raised to its regular rib knitting position.

10 Rubber yarn cutter and clamp

Another feature of the invention is the cutter and clamp C used to hold the rubber yarn when it is not being laid in the rib fabric. This cutter and clamp which is of the multiblade type, as 20 shown in patent to Trudel No. 1,191,100, dated July 11, 1916, is located just inside the verge of the dial at a point, circumferentially speaking, just about 45° after the yarn feeding finger 185 (Fig. 6) and is carried on an arm 200 extending 25 from the latch ring at the front of the machine to the cross bar which supports the gears for the dial. The cutter is normally held in closed position by a coiled spring 201 which extends upwardly from the upper end of the movable member to a 30 small arm 202 projecting from the cover 203 over the bevelled gear on the upper end of the dial drive shaft. The lower end of the movable member is in the form of a hook pointed radially outward and lies between two stationary members, 35 one having a bevelled end forming a cutting edge. The lowering of the hook causes the yarn to be caught in the hook where the yarn is being fed from an advanced position such as that of the rubber yarn finger and the yarn finger is raised 40 to withdraw the yarn. To operate the cutter and clamp to engage and release the yarn, mechanism is provided which is operated from cams on the auxiliary pattern drum 20. This mechanism includes a lever 204, one end of which overlies the 45 upper end of the hook and which is pivoted on a stud on the latch ring 550. The other end of the lever 204 extends rearwardly from the pivot point and is connected by a link 205 to a bell crank 50 lever 14 associated with the auxiliary striping drum 20. This linkage is so arranged that when the bell crank lever rides onto a cam on the drum 20, the cutter is opened, and when it rides off the cam, the tension spring 201 attached to the upper end of the hook closes the cutter and clamp.

55 Safety device for cutter and clamp

In a manner somewhat similar to that of the safety catch for the rubber yarn finger 185, a safety device is provided for the cutter and clamp 60 which prevents the clamp opening except when actuated from a cam on the auxiliary pattern drum 20 during the making of the rib fabric. This device, like that for the rubber yarn finger, is controlled from another element on the machine and comprises a latch member 147 (see Fig. 2) pivoted on the link 205 above the slot in the link in which the pin on the bell crank lever travels and having a notch or shoulder 148 at its lower end which is positioned to engage the upper 65 edge of the bell crank lever arm by a tension spring 149 operating on the laterally extending curved arm 147a of the latch member 147. The curved arm 147a is connected by a wire 206 to the thrust rod 125 which adjusts the vertical eleva- 70 75

tion of the dial D. The connection between the wire 206 and the thrust rod 125 consists of a stud 125^a projecting laterally from the side of the thrust rod 125 and having a hole through which 5 the wire passes. On the wire 206 on the side of the stud 125^a away from the safety latch 147 is an adjustable collar 206^a which is so set as to pull the wire 206 upward whenever the thrust rod 125 is raised from its lowermost or rib knitting position. Such a pull on the wire 206 disengages the 10 shoulder 148 of the latch 147 from the bell crank lever 14 so that any movement of the bell crank lever thereafter will merely cause idling of the pin in the slot of the trip link 205 and will not cause 15 the clamp to release the rubber yarn.

Operation of the machine

The construction of the machine having been set forth, its operation will now be described. 20 Assuming that the machine has just finished making the automatic welt such as described in the above-mentioned patent to Robert W. Scott, No. 1,641,101, the main pattern drum 120 is racked forward as the machine goes into rib knitting. This rack of the main pattern drum drops the dial raising thrust rod 125 to its lowermost position, which not only lowers the dial to rib knitting position but also allows the safety catch 147 for the cutter and clamp to latch on 25 top of the bell crank arm thereby connecting the cutter and clamp operatively to its cams on the auxiliary pattern drum 20. This racking of the main pattern drum 120 also allows the thrust rod 463 to drop off its cam surface 521, thus not 30 only operating the sinkers further in in order to get the added thrust necessary for the teeth on the sinkers to push the rib fabric down in the fabric tube, but also allowing the latch of the safety device for the rubber yarn finger 185 to engage on top of its bell crank arm, thus operatively 35 connecting the rubber yarn finger with the bell crank lever.

This rack of the main pattern drum also shifts the lever 461 from its position against the main pattern drum 120 onto the low cam 527 operating 40 the link 177 to withdraw the cam 26 from the operative position occupied during the knitting of the welt to an inoperative position in which the cam 26 clears the butts of all the cylinder needles. The cam 26 is placed in operative position 45 at the beginning of the welt as at that time the jackless needles when coming out of the knitting wave with the ever-active needles, the needles are intercalated one and one—tend to catch a yarn end from the neighboring ever-active needles and hold it, and the cam 26 clears the latches of the jackless needles if there are 50 any yarns on them. While the cam 26 is in operative position during the knitting of the welt the lug 176 on wire 177 is away from the pin 178 55 on bracket 183 but at this time the auxiliary drum 20 is stationary with the bell crank lever 14 connected to the rod 460 in engagement with the drum 20 so that the blade 180 is positioned to engage the pin 178 and hold the cam 184 clear of the long butt needles. As the needles have not 60 been raised to clear their latches, the draw down cam 8, while lowering the needles, does not cause the loops to be cast off. Shifting of the cam 26 to its inoperative position causes the lug 176 to 65 be moved nearer to the pin 178 but, as shown in Fig. 7, not in engagement therewith so that the position of the bracket 183 and the cams 8 and 184 is still determined by the blade 180.

This rack on the main pattern drum going into

the rib fabric drops the lever 530 from the high cam on the main pattern drum 120 to the intermediate cam lowering the pawl into engagement with the rack 21 of the auxiliary drum 20 which thereupon racks the auxiliary drum 20 once for 5 each revolution of the needle cylinder while the main pattern drum remains at rest. The racking of the auxiliary drum 20 continues until the low tooth of the rack 21 is reached whereupon racking of the drum 20 ceases as the position of 10 the lever 530 on the intermediate height cam prevents the pawl engaging the low tooth. This first rack of the auxiliary striping drum 20 causes the bell crank lever 14 associated with the cylinder raising tube 197 to drop off its cam 863 15 (Fig. 10) lowering the cylinder raising tube 197 and the needle cylinder 260 to their lowest positions.

During the second course of rib knitting the operations necessary to commence actual feeding of the rubber yarn begin. During the rack of the auxiliary striping drum 20 which occurs during this second course of rib fabric, the rubber yarn finger 185 is lowered to operative position 20 by its bell crank lever 14 being raised by the cam 25 858 on the auxiliary striping drum 20 to raise the bent thrust rod 462 and operate the lever 142 to lower the yarn finger 185. The operation of the yarn finger lever 142 causes the short pivoted lever 155 to push radially outward against the 30 upwardly bent end of the curved cam plate 157 on the top of the dial cap, and operate the pivoted cam 152 in the dial cap to a position which shifts the hook portions *a* of the dial needles radially outward about one-sixteenth of 35 an inch beyond the verge of the dial. At the same time cam 859 on the auxiliary striping drum 20 acting through its bell crank lever 14, the rod 460 and blade 180 releases the auxiliary draw down cam bracket 183 so that it is shifted 40 to its innermost operative position by the coil spring 182. About one-third of a revolution later the cam 184 engages the long butt or butts of the idle cylinder needle or needles N² which are to catch the rubber yarn and raises them to 45 the level shown in Fig. 5 at the left of the figure. Shortly after the isolated needles N² are thus raised and pass the rubber yarn finger they are drawn down by the fixed draw down cam 151. The yarn guide arm 190 is operated during the 50 same rack of the auxiliary striping drum 20 as the bell crank lever 14 connected to the guide arm 190 moves from the high portion to the low portion of the cam 860 and, acting through the link 195 and pivoted guide arm 190, lowers the 55 guide 191 to its intermediate position. Before the end of this rack of the auxiliary striping drum 20, the bell crank lever 14 connected to the link 195 moves from the low portion of the cam 860 onto the surface of the striping drum 20, 60 lowering the guide 191 to its lowermost position and giving additional slack at or about the time that the clamp is operated to release the rubber yarn. The release of the rubber yarn by the clamp comes before the end of this rack of the auxiliary striping drum as the bell crank lever 14, Fig. 2, rides up onto cam 861 on the auxiliary striping drum 20, raising the trip link 205 and operating the pivoted lever 204 to open the 65 clamp.

The insertion of the draw down cam 8 and the isolating cam 184 into operative position during the second course of rib knitting to raise the selected idle cylinder needles N² to take the rubber yarn, has already been described. On 70 75

the same rack of the auxiliary striping drum 20 the bell crank lever 14 controlling the blade 180 moves off the cam 859 causing the blade 180 to press against the pin 178 and retract the auxiliary draw down cam bracket 183 sufficiently to bring the isolating cam 184 clear of the long butt needles but still leaving the regular draw down cam 8 in operative relation with all the cylinder needle butts. The insertion of the isolating cam 184 and the fixed draw down cam 151 located in back of the dropper post at the front of the machine and engaging the long butt needles N² only, cause the special long butt needles N² to be raised for one course only to take the rubber 10 yarn and to be drawn down to resume the idle path which the other idle cylinder needles took during the first course of rib fabric, all the idle needles thereafter continuing that idle path for the balance of the rib fabric. The path of the 20 idle cylinder needles opposite the dial needles and the manner of separating these needles from the active or intercalated cylinder needles are shown and described by the Robert W. Scott Patent No. 1,641,101.

25 The feeding of the rubber yarn continues for any desired number of courses, the yarn feeding in below the dial needle hooks as shown in Fig. 3, and as shown in Fig. 4 in solid line portions. The revolution of the auxiliary striping drum 20 being timed to occupy more than the number of courses desired with rubber inlay yarn, the operation of the machine will continue in the following manner:

30 Shortly before the desired number of courses containing the rubber yarn is made, the bell crank lever 14 associated with the guide 191 for the rubber yarn rides from the surface of the auxiliary pattern drum 20 up onto a high cam (860—Fig. 10), thereby raising the guide 191 or the yarn 35 supply reel to its highest position and establishing the maximum length of path for the rubber yarn from the supply of the rubber yarn on the cone or bobbin to the yarn finger 185. On the same rack of the auxiliary pattern drum 20 the bell crank lever 14 operating the rubber yarn finger 185 drops from the cam 858 on the drum 20 and the arm 142 is drawn upward by its tension spring 144 to the dotted position shown in Fig. 8. This creates the slack in the rubber yarn 40 which is taken advantage of when the rubber yarn is inserted in the making of the next stocking.

45 Immediately after the raising of the yarn finger 185 the continued revolution of the needle cylinder 260 brings the rubber yarn into the diagonal position shown in dotted lines in Fig. 4, the hook member of the cutter and clamp in the meantime having been lowered to its open position because the rack of the striping drum 20 raised the corresponding bell crank lever 14 onto 50 the cam 862, Fig. 10. The continuation of this rack moves the striping drum cam 862 from under the bell crank lever, thus releasing the hook member to be drawn upward by tension spring 281 to cut and clamp the rubber yarn. As soon as 55 the rubber yarn has been cut and clamped, the needle cylinder 260 can be raised while the rib knitting is still going on, to cause effective action of the sinker teeth on the fabric without the rubber yarn and without affecting the length of the 60 stitch. The needle cylinder is raised at this time by the cam 863 on the auxiliary striping drum 20 operating its associated bell crank lever 14 and thereby operating the link 199 and the cylinder raising lever 196 from the position shown in 65 Fig. 1.

The striping drum 20 continues to rack around, while the machine continues to make rib fabric, until the usual low or timing tooth is reached. Thereafter the racking pawl for the auxiliary drum idles back and forth without being able to reach the low tooth. The means for preventing the racking pawl from engaging the low tooth at this time comprise an idling lever 530 pivoted on the axis of the auxiliary drum 20 and having a toe engaging the cams at one cam position of the 10 main drum 120. There is a long high cam on the main drum opposite this idling lever which cam extends completely around the circumference of the drum except for a short section and this cam is of such a height that when the toe of the 15 idling lever is on it the racking pawl will be held up out of engagement with all the teeth in the striping drum rack wheel 21. Part of the gap between the ends of this high cam is occupied by a low or intermediate cam which is of such a 20 height as to permit the racking pawl to engage all the teeth on the auxiliary drum rack wheel 21 except the low tooth. This main drum low cam comes immediately after the high cam when the 25 direction of rotation of the main drum is considered, and these cams are so located that the idling lever 530 is resting on the low cam during the making of the rib fabric. When the idling lever 530 drops off this low cam down onto the 30 surface of the drum 120, the pawl will be lowered 35 to a position where it can get not only the high tooth but also the low tooth of the auxiliary drum rack wheel 21.

When the usual main pattern chain of the machine (not shown) indicates that the correct number of courses for the rib fabric has been completed, the lugs on the pattern chain, acting through the usual main rack wheel causes the main pattern drum 120 to be racked forward several times for the purpose of changing the knitting 40 from rib to plain. In a machine made according to this invention, the first of these racks at this point in the manufacture of the stocking causes the idling lever 530 to pass off the low cam down onto the surface of the drum 120 permitting the auxiliary drum racking pawl to drop into engagement with the low tooth of the auxiliary drum rack 21 and rack the auxiliary drum 20 forward three or four teeth. The racking of the auxiliary striping drum 20 at this point causes the bell crank lever 14 controlling the elevation of the needle cylinder 260 during rib knitting to drop off its cam 863 thus releasing the needle cylinder for control by the usual mechanisms during plain knitting. The second rack of the main pattern drum causes the idling lever 530 to ride up onto the long high cam which lifts the auxiliary drum racking pawl out of operative relation with all the teeth on the auxiliary drum rack 45 wheel 21, thereby stopping the auxiliary striping drum 20. This high cam stays under the toe of the idling lever 530 until the machine has finished the welt and is ready to begin rib knitting on the 50 next stocking.

If it is desired to use the auxiliary striping drum 20 at any time during plain knitting, the high cam holding the idling lever 530 in position to prevent operation of the drum 20 is removed at the appropriate point or points on the circumference of 55 the drum 120 and blank spaces left or low cams inserted as needed. The racks of the main pattern drum 120 at the time of transfer from rib to plain fabric also raise the thrust rod 483 which has been causing the extra long thrust of toothed 60 65 70 75

sinkers onto cam 521, thereby disengaging the safety catch on the thrust rod 462 and the rubber yarn finger 185 so that the rubber yarn finger cannot be lowered into feeding position if the 5 striping drum 20 should be operated during the making of the balance of the hose. This also makes it possible to use the striping drum 20 for patterns in the leg without the rubber yarn finger 185 interfering. These racks of the main pattern 10 drum also raise the dial D by means of the long thrust rod 125, releasing the catch of the safety latch on the thrust rod 205 for the rubber yarn cutter and clamp so that the cutter and clamp cannot be operated, no matter what cams may 15 inadvertently or otherwise be brought into engagement with the corresponding bell crank lever. Where the auxiliary pattern drum 20 is also used for patterns in the leg of the stocking the yarn fingers for the pattern yarns are held inactive during rib knitting by push rods operated from the main pattern drum as usual so that they are not affected by the operation of the auxiliary drum 20 controlling the rubber yarn at that time.

What we claim is:

- 25 1. Rubber yarn feeding mechanism for a knitting machine comprising a yarn supply, a finger for feeding the yarn, means operating said finger to introduce the yarn by moving the yarn finger in a direction to lengthen the yarn path between the yarn supply and finger and means for lessening the length of the yarn path between the yarn supply and finger to reduce the tension on said yarn during the introduction of the yarn to the needles.
- 30 2. Rubber yarn feeding mechanism for a knitting machine comprising a yarn supply, a finger for feeding the yarn, a guide for said yarn between said yarn supply and finger and means for shifting said guide to lessen the path of the yarn between the yarn supply and said finger as said finger is operated to introduce the yarn and for operating said guide to lengthen said yarn path while said yarn finger remains in feeding position.
- 35 3. Rubber yarn feeding mechanism for a circular knitting machine, comprising a feeding finger for the rubber yarn, in combination with a guide for said yarn between said yarn supply and finger and mechanism adapted to move said guide toward said finger to produce slack in the yarn between the guide and finger and to move said guide away from said yarn finger to lengthen the yarn path while said yarn finger is in feeding position.
- 40 4. In a circular knitting machine, rubber yarn feeding mechanism comprising a finger for the rubber yarn and a guide for said yarn continuously associated with said yarn and located prior to said finger, in combination with a rubber yarn supplying means and mechanism adapted to shorten the path of travel between the rubber yarn supplying means and the finger by moving the guide as said yarn finger is moved to feeding position.
- 45 5. In a circular knitting machine, rubber yarn feeding mechanism comprising a finger for feeding the rubber yarn and a guide directing the rubber yarn to the finger, in combination with means for moving said finger to operative position and for simultaneously moving said guide toward said finger.
- 50 6. In a circular knitting machine, rubber yarn feeding mechanism comprising a finger for feeding said yarn and a guide continuously associated with said yarn and about which said yarn is deflected in moving to said yarn finger, in combina-

tion with means for moving said guide so as to reduce the angle through which the yarn is deflected at said guide and thereby produce slack between the guide and the finger as said yarn finger is moved to feeding position. 5

7. In a circular knitting machine, rubber yarn feeding mechanism comprising a finger for feeding rubber yarn and a guide directing said rubber yarn to the finger, in combination with means for moving simultaneously said finger to operative 10 position and said guide so as to produce slack between the finger and the guide.

8. In a circular knitting machine, rubber yarn feeding mechanism comprising a finger for feeding said yarn having operative and inoperative 15 positions, a rubber yarn supply and a guide located between said rubber yarn supply and said finger, in combination with means for moving said guide so as to change the length of the path of travel of the yarn between the supply and the 20 finger, said means being adapted to move the guide so as to lessen the path of travel as the finger moves to operative position.

9. In a circular knitting machine having cylinder and dial needles cooperating in the knitting 25 of rib fabric, a finger for feeding rubber yarn in the rib fabric, a rubber yarn supply, a guide for the rubber yarn between the supply and finger, means for operating said finger to introduce the rubber yarn into the rib fabric and to withdraw 30 the rubber yarn therefrom, means operating/said yarn guide to lessen the yarn path between the rubber yarn supply and the finger upon the introduction of the rubber yarn into the rib fabric and means to operate said guide to lengthen said rubber 35 yarn path during the feeding of the rubber yarn.

10. In a circular rib knitting machine, a series of dial needles, a series of cylinder needles comprising one series opposite the dial needles inactive during rib knitting and another series intercalated between the dial needles used during rib knitting, both of said series of cylinder needles cooperating in the knitting of plain fabric, and a yarn finger adapted to feed rubber 45 yarn just below the dial needles, in combination with one or more special needles in the group of cylinder needles opposite the dial needles, and means adapted to operate said special needles to take the rubber yarn and draw it under the dial 50 needles.

11. In a circular rib knitting machine having dial and cylinder needles cooperating to knit rib fabric and cylinder needles inactive in the knitting of the rib fabric, a rubber yarn supply, a finger for feeding the rubber yarn between the loops of the rib and plain wales during rib knitting, a guide for the rubber yarn between said yarn supply and finger, means for operating an inactive cylinder needle to take the rubber yarn 60 and means operating the yarn guide to lessen the yarn path between the yarn supply and finger as said needle takes the rubber yarn. 65

12. In a circular rib knitting machine having dial and cylinder needles cooperating to knit rib 70 fabric and cylinder needles inactive in the knitting of the rib fabric, a rubber yarn supply, a finger for feeding the rubber yarn between the loops of the rib and plain wales during rib knitting, a guide for the rubber yarn between said yarn supply and finger, means for operating an inactive cylinder needle to take the rubber yarn, means operating the yarn guide to lessen the yarn path between the yarn supply and finger as said needle takes the rubber yarn and to lengthen

- the yarn path while the rubber yarn is being fed.
13. In a circular rib knitting machine having dial and cylinder needles cooperating to knit rib fabric and cylinder needles inactive in the knitting of the rib fabric, a rubber yarn supply, a finger for feeding the rubber yarn between the loops of the rib and plain wales during rib knitting, a guide for the rubber yarn between said yarn supply and finger, a cutter and clamp mechanism for holding the rubber yarn end when the yarn is not being fed, means for operating said cutter and clamp mechanism to take and release the yarn, means operating an inactive cylinder needle to take the rubber yarn and means operating the yarn guide to lessen the tension on the rubber yarn prior to its release by said cutter and clamp mechanism.
14. In a circular rib knitting machine, a yarn finger for feeding rubber yarn during rib knitting, a cutter and clamp mechanism for said yarn, a thrust rod for operating said cutter and clamp mechanism, an auxiliary pattern drum, a lever operated by said auxiliary pattern drum for operating said thrust rod, means for operatively connecting said lever and thrust rod, a main pattern drum and means operated by said main pattern drum controlling the operation of said connecting means for preventing operation of said thrust rod during plain knitting.
15. In a circular rib knitting machine having dial and cylinder needles cooperating to knit rib fabric and cylinder needles inactive during the knitting of rib fabric, a yarn finger for feeding a yarn between the loops of the rib and plain wales during rib knitting, and means for operating an inactive cylinder needle to take and hold said yarn during a plurality of courses of rib knitting.
16. In a circular rib knitting machine having dial and cylinder needles cooperating to knit rib fabric and cylinder needles inactive during the knitting of rib fabric, a yarn finger for feeding a yarn between the loops of the rib and plain wales during rib knitting, means for operating an inactive cylinder needle to take and hold said yarn during a plurality of courses of rib knitting and means holding down the free portion of the yarn between said yarn finger and the fabric.
17. In a circular rib knitting machine having dial and cylinder needles cooperating to knit rib fabric and cylinder needles inactive during the knitting of rib fabric, a yarn finger for feeding a yarn between the loops of the rib and plain wales during rib knitting, means for operating an inactive cylinder needle to take and hold said yarn during a plurality of courses of rib knitting and means projecting said dial needles to hold down the free portion of the yarn between said yarn finger and the fabric.
18. In a circular rib knitting machine having dial and cylinder needles cooperating to knit rib fabric and cylinder needles inactive during the knitting of rib fabric, a yarn finger for feeding a yarn between the loops of the rib and plain wales during rib knitting, means for operating an inactive cylinder needle to take and hold said yarn during a plurality of courses of rib knitting and means projecting said dial needles over said yarn and partially withdrawing said dial needles while said dial needles hold down said yarn.
19. In a circular rib knitting machine having dial and cylinder needles cooperating to knit rib fabric and cylinder needles inactive during the

knitting of rib fabric, a yarn finger for feeding a yarn between the loops of the rib and plain wales during rib knitting and means projecting said dial needles over said yarn and then withdrawing said dial needles from the paths taken by the inactive cylinder needles when raised while continuing said dial needles in position to hold down said yarn prior to the knitting wave.

20. In a circular knitting machine, a yarn finger for feeding rubber yarn during rib knitting, a thrust rod for operating said yarn finger, an auxiliary pattern drum, a lever operated by said auxiliary pattern drum for operating said thrust rod, means for operatively connecting said lever and thrust rod, a main pattern drum and means operated by said main pattern drum controlling the operation of said connecting means for preventing operation of said thrust rod during plain knitting.

21. In a circular knitting machine, a yarn finger for feeding rubber yarn during rib knitting, a thrust rod for operating said yarn finger, an auxiliary pattern drum, a lever operated by said auxiliary pattern drum for operating said thrust rod, means for operatively connecting said lever and thrust rod, a main pattern drum and means operated by said main pattern drum preventing connection of said lever and thrust rod during plain knitting.

22. In a circular rib knitting machine, a yarn finger for feeding rubber yarn during rib knitting, an auxiliary pattern drum, means operated by said auxiliary pattern drum for operating said yarn finger, a main pattern drum and means operated by said main pattern drum preventing operation of said yarn finger upon operation of said auxiliary pattern drum during plain knitting.

23. In a circular rib knitting machine, a yarn finger for feeding rubber yarn during rib knitting, a thrust rod for operating said yarn finger, an auxiliary pattern drum, a lever operated by said auxiliary pattern drum for operating said thrust rod, a latch for connecting said lever and thrust rod, a main pattern drum and means operated by said main pattern drum preventing said latch connecting said lever and thrust rod during plain knitting.

24. In a circular rib knitting machine having a dial and a cylinder with needles therein cooperating to knit rib fabric, a yarn finger for feeding rubber yarn between the loops of the rib and plain wales, pattern mechanism and means controlled by said pattern mechanism for operating said yarn finger to introduce the rubber yarn and for increasing the spacing between the cylinder and dial for the passage of the fabric upon the introduction of the rubber yarn to the rib fabric.

25. In a circular rib knitting machine having a dial and a cylinder with needles therein cooperating to knit rib fabric, a yarn finger for feeding rubber yarn between the loops of the rib and plain wales, pattern mechanism controlling the operation of said yarn finger and means operated by said pattern mechanism shifting said cylinder from said dial and increasing the spacing between the cylinder and dial for the passage of the rib fabric upon the introduction of the rubber yarn to the rib fabric.

26. In a circular knitting machine having a dial and a cylinder with needles therein cooperating to knit rib fabric, a yarn finger for feeding rubber yarn between the loops of the rib and plain wales, pattern mechanism controlling the operation of said yarn finger and means operated by

said pattern mechanism lowering the cylinder from the dial upon the introduction of the rubber yarn during the knitting of rib fabric.

27. In a circular knitting machine having a dial and a cylinder with needles therein cooperating to knit rib fabric, a yarn finger for feeding rubber yarn between the loops of the rib and plain wales, pattern mechanism controlling the operation of said yarn finger and means operated by

said pattern mechanism operating said yarn finger to present and withdraw the rubber yarn and to increase and decrease the spacing between the cylinder and dial as the rubber yarn is presented and withdrawn during the knitting of rib fabric. 5
